**COMBINED FAN BLADE AND HUB OR
SIMILAR ARTICLE**

George S. Dickinson, Fairfield, Conn., assignor to General Electric Company, a corporation of New York

Filed Apr. 12, 1966, Ser. No. 1,859

Term of patent 14 years

(Cl. D62--4)

Fig. 1.

Fig. 2.

Fig. 3.

Fig. 4.

FIG. 1 is a front perspective view of a fan blade and hub embodying my new design;

FIG. 2 is a side elevational view of the fan blade and hub shown in FIG. 1;

FIG. 3 is an enlarged front elevational view of the fan blade and hub shown in FIG. 1 with the outer ends of the blades removed; and

FIG. 4 is an enlarged rear elevational view of the fan blade and hub shown in FIG. 1 with the outer ends of the blades removed.

I claim:

The ornamental design for a combined fan blade and hub or similar article, substantially as shown.
